UNITED STATES PATENT OFFICE.

BERTRAM K. HOLLISTER, OF CHICAGO, ILLINOIS.

SURGICAL LIGATURE AND PACKAGE.

No Drawing.

Application filed January 27, 1919. Serial No. 273,439.

To all whom it may concern:

Be it known that I, BERTRAM K. HOLLISTER, a citizen of the United States, residing at Chicago, in the county of Cook and State of Illinois, have invented certain new and useful Improvements in Surgical Ligatures and Packages, of which the following is a specification.

The present invention relates to putting up 10 in commercial form surgical ligatures, particularly those made of the material commonly known as catgut, and constitutes an improvement upon the invention described and claimed in my U. S. Patent No. 1,239,690 15 of September 11, 1917.

The object of the invention is to improve the product, by the use of a special sterilizing liquid embraced within the invention, whereby the antiseptic effect is increased 20 and other advantages secured.

As in my prior patent referred to, I preferably employ as the base of the sealing liquid, or liquid in which the catgut ligature is immersed, or partially immersed, 25 (which two terms are used interchangeably in the present specification, since it is not necessary that the entire ligature be completely immersed at all positions of the container), a highly refined kerosene of 30 which the initial boiling point is preferably above 140° to 150° C. I have now found that a good grade of highly refined kerosene having an initial boiling point of about 184° C., is especially well suited for the 35 purpose. The initial boiling point of the kerosene used may vary more or less (say 175 to 184° C.), but, preferably, there should not be any large fraction of the kerosene boiling below about 184° C. Highly refined kerosene of this character gives better 40 results than kerosene of lower initial boiling point.

In accordance with the present invention, the sealing liquid is preferably prepared by 45 first dissolving one part of red mercuric iodid in about 1200 parts (by weight) of chloroform, chemically pure chloroform being preferred for the purpose. To one part, by volume, of this liquid, there is added nine 50 parts, by volume, of kerosene of the character above stated, (although other hydrocarbon oils may be employed, especially distillates of petroleum, after suitable purification). This produces a solution containing approximately one part of mercuric iodid in 10,000 parts of solution (by weight). The

liquid produced is a highly stable solution, which exerts an antiseptic and germicidal action, and also possesses many of the advantages of the sealing liquid set forth in 60 my prior patent above referred to, and does not possess the disadvantages which would be present if free iodin were employed. It may be noted that mercuric iodid itself is 65 not soluble in kerosene, but is readily soluble in chloroform, and the chloroform solution of mercuric iodid mixes readily with the oil, so that I produce, by the method disclosed, a solution of the iodid in a vehicle consisting 70 largely of kerosene.

The other materials, as specified in my prior patent, can be employed if desired, and if employed, will further improve the sealing liquid. Chloroform (say 33%), oils which are antiseptic, or oils which mask the 75 kerosene odor, e. g., oil of eucalyptus (say 1%), oil of peppermint (say 1%), oil of pine needles (say 5%), or mixtures of such oils (say 5%) or thymol or menthol (say 1% or 2%), or other antiseptic or germicidal 80 material (e. g., "pyotannin") are mentioned as materials which can be so added; the percentages stated are based on the amount of kerosene used, and are given by way of 85 example.

As in my prior patent, I place the catgut ligature, which may have been previously colored or otherwise treated if desired, in a glass tube. I then fill, or partially fill the tube with the above described sealing liquid, 90 then seal and sterilize the tube in any well known manner. At the time of use the tube is broken open, a scratch being made intermediate the ends of the tube to facilitate this 95 operation, as in the usual manner, and the ligature is then removed from the tube and employed in the usual manner.

Kerosene, of the character referred to, consists almost exclusively of saturated hydrocarbons of the paraffin series.

What is claimed is:

1. A liquid suitable for holding ligature material of the nature of catgut, comprising kerosene, the major portion of which boils at a temperature above 184° C., carrying 105 therein a small amount of mercuric iodid and a solvent for the latter which is readily miscible with the kerosene.

2. A liquid suitable for holding catgut ligatures, said liquid comprising red mercuric iodid dissolved in chloroform and 110 mixed with kerosene.

3. A liquid suitable for holding ligatures in the nature of catgut, comprising red mercuric iodid, chloroform and kerosene, the amount of chloroform being about ten per cent by volume of the mixture, and the entire liquid having a content of mercuric iodid equal to about one part in 10,000.

4. A liquid suitable for holding ligature

material of the nature of catgut, comprising kerosene, the major portion of which kerosene boils at a temperature of about 184° C., said liquid also containing red mercuric iodid. 10

In testimony whereof I have signed my name to this specification.

BERTRAM K. HOLLISTER.
